United States Patent

Des. 237,113
Patented Oct. 7, 1975

237,113

INTRAVASCULAR INFUSION UNIT

Seymour Hoff and Sharon Kehr, San Jose, and Richard G. Buckles, Menlo Park, Calif., and Denis H. Nelson, Wheaton, Ill., assignors to ALZA Corporation

Filed Nov. 14, 1973, Ser. No. 415,691

Term of patent 14 years

Int. Cl. D24—02

U.S. Cl. D83—1 F

FIG. 1

FIG. 2

FIG. 3

FIG. 4

FIG. 5

FIG. 6

FIG. 7

FIG. 1 is a perspective view of an intravascular infusion unit showing our new design.

FIG. 2 is a front elevational view of the design.

FIG. 3 is a rear elevational view of the design.

FIG. 4 is a side elevational view of the design looking from the left in FIG. 2.

FIG. 5 is a side elevational view of the design looking from the right in FIG. 2.

FIG. 6 is a top plan view of the design.

FIG. 7 is a bottom plan view of the design.

We claim:

The ornamental design for an intravascular infusion unit, as shown.
